US00D585021S

(12) **United States Design Patent**
Surrette

(10) **Patent No.:** **US D585,021 S**
(45) **Date of Patent:** **** Jan. 20, 2009**

(54) **GAS RECOMBINATION CAP**

(75) Inventor: **John D. Surrette**, Springhill (CA)

(73) Assignee: **Surrette Battery Company Ltd.**,
Springhill, Nova Scotia (CA)

(**) Term: **14 Years**

(21) Appl. No.: **29/284,185**

(22) Filed: **Aug. 31, 2007**

(51) **LOC (9) Cl.** **13-01**

(52) **U.S. Cl.** **D13/119**

(58) **Field of Classification Search** **D13/119,**
D13/103, 118, 199; D9/453; D10/80; D12/197;
D23/260, 262; 220/4.14, 86.1, 254, 288;
429/53, 54, 57, 86, 96–100, 163, 176

See application file for complete search history.

(57) **CLAIM**

The ornamental design for gas recombination cap, as shown and described.

DESCRIPTION

FIG. 1 is a top perspective view of a gas recombination cap.

FIG. 2 is a bottom perspective view of a gas recombination cap.

FIG. 3 is a front view of a gas recombination cap.

FIG. 4 is a side view of a gas recombination cap.

FIG. 5 is a top view of a gas recombination cap; and,

FIG. 6 is a bottom view of a gas recombination cap.
